UNITED STATES PATENT OFFICE.

JOHN MINOR BOTTS LEWIS, OF LYNCHBURG, VIRGINIA.

DRINKING APPARATUS.

1,282,886.

Specification of Letters Patent. Patented Oct. 29, 1918.

Application filed February 14, 1918. Serial No. 217,125.

To all whom it may concern:

Be it known that I, JOHN M. B. LEWIS, a citizen of the United States, residing at Lynchburg, in the county of Campbell and State of Virginia, have invented certain new and useful Improvements in Drinking Apparatus, of which the following is a specification.

My invention relates to improvements in drinking receptacles or troughs for cattle, horses, and the like.

An important object of the invention is to provide simple and efficient straining means for the overflow and drain outlet of the receptacle.

Other objects and advantages of the invention will be apparent during the course of the following description.

In the accompanying drawings forming a part of this specification and in which like numerals are employed to designate like parts throughout the same,

Figure 1 is a plan view of apparatus embodying my invention, a portion of the cover being broken away, for the purpose of illustration,

Fig. 2 is a longitudinal sectional view taken on line 2—2 of Fig. 1,

Fig. 3 is a central longitudinal vertical section through the same,

Fig. 4 is a transverse sectional view taken on line 4—4 of Fig. 1, and,

Fig. 5 is a perspective view of the strainer plate.

In the drawings, wherein for the purpose of illustration, is shown a preferred embodiment of my invention, the numeral 10 designates a drinking receptacle or bowl, the upper end of which is open, as shown.

This bowl has its lower portion or bottom formed in the rear portion 11, which is inclined forwardly, to meet with a rearwardly inclined forward portion 12, which is curved in cross-section, as shown more clearly in

Fig. 3. Formed in the rear portion 11 is a depending inclined passage or pocket 13, which is substantially V-shaped in cross-section and increases in depth toward an outlet. The elevated end of this pocket

terminates near or at the point of union of the forward and rear bottom portions 11 and 12. The passage or pocket 13, at one end, is provided with an outlet opening 14, discharging into a lateral tubular extension

15 of a drain conduit 16. This lateral extension 15, at its lower end, discharges into the conduit 16. The drain conduit 16 projects interiorly above the bottom portion 11, within the receptacle 10, forming an overflow conduit 17, the upper end of which determines the maximum water level of the drinking receptacle 10, as shown. It is thus apparent that the overflow water from the conduit 17 and the drain water from the passage or pocket 13, both preferably discharge through the drain conduit 16, which may be connected with a suitable pipe (not shown), discharging at a suitable point.

The numeral 18 designates a strainer element or plate, having apertures 19. It is obvious that other strainer material may be employed, such as wire gauze or the like. This strainer element or plate 18 is preferably arranged diagonally within one corner of the drinking receptacle 10, in advance of the drain outlet 14 and over-flow conduit 17, as shown. One end or edge of the strainer element or plate 18 is arranged behind a retaining lug 20 preferably cast upon the inner surface of the side wall of the drinking receptacle, as clearly shown in Fig. 1. The strainer element or plate 18 extends across the drain passage or pocket 13, and is provided with an apertured extension 21, of a suitable shape and size for fitting within this passage or pocket, as clearly illustrated in Fig. 4. At its upper end, the strainer element or plate 18 is provided with an imperforate plate 22, preferably formed integral therewith. This plate is preferably triangular, as shown in Fig. 1, to properly fit within the corner of the drinking receptacle.

Arranged within the rear portion of the drinking receptacle 10 is a water inlet conduit or valve casing 23, preferably vertically arranged with its upper discharge end disposed a substantial distance above the upper intake end of the over-flow conduit 17, as shown in Fig. 4. The conduit 23 has a drain or weep port 23', as shown. The inlet conduit or valve casing 23 is preferably cast integral with the bottom 11, and the lower portion thereof has an L-shaped port 25', discharging into the main bore thereof. Water is supplied to the port 25', by a pipe 24, through the medium of a coupling 24', as shown. A bolt 26' has one end thereof

extending into the port 25', and is adjustable therein, to control the volume of water passing therethrough.

The passage of the water through the port 25' is controlled or regulated by a valve 25, having connection with a rod 26, extending upwardly through an aperture formed in a cap 27, carried by the inlet conduit 23. Though the inlet valve is shown 10 within the drink receptacle, its location is not intended to be limited to that location but may be placed anywhere within the supply conduit or its connections outside of the drinking receptacle. The cap 27 is suitably spaced from the upper end of the inlet conduit to permit of the discharge of the water therefrom, in a downwardly direction.

The numeral 28 designates a cover for the 20 drinking receptacle 10 which may be advantageously provided at its forward end with an up-turned lip 29. The rear end of the cover is hinged to the receptacle 10, as shown at 30, for swinging movement in a 25 vertical plane.

The opening 14 of the passage or pocket 13, is closed and opened by a vertically movable valve 31, the upper end of which is tapered, as shown at 32. The valve 31 is 30 shown in its lowermost position in Fig. 2, the opening 14 being open whereby the drinking receptacle is drained. When the valve is moved upwardly it closes the opening 14 whereby the receptacle is adapted 35 to hold the water. The valve 31 is adapted to be suitably moved by an upstanding rod 33, connected therewith and having operative connection, as shown at 34, with the cover 28. The valve rod 26 is operatively 40 connected with the cover 28, as shown at 35.

The operation of the apparatus is as follows:

When the animal, such as a cow or horse, desires to drink, it engages the cover 28 with 45 its muzzle and elevates the cover, thus gaining access to the interior of the drinking receptacle 10. This upward movement of the cover 28 operates the valve 31, for shifting the same to the closed position, and simultaneously moves the valve 25, to the open 50 position, whereby the water will pass from the discharge end of the inlet conduit 23 and be discharged into the drinking receptacle.

It is obvious that the strainer element or 55 plate 18 and extension 21 serve as common means for protecting the drain passage or pocket 13 and the over-flow conduit 17, and preventing trash or the like from becoming clogged therein.

60 It is to be understood that the form of my invention herewith shown and described is to be taken as a preferred example of the same, and that various changes in the shape, size, and arrangement of parts may be resorted to without departing from the spirit

of the invention or the scope of the subjoined claims.

Having thus described my invention, I claim:

1. In apparatus of the character described, 70 a drinking receptacle provided in its bottom with a drain outlet, an overflow conduit for the drinking receptacle arranged near the drain outlet, a cover hinged to the drinking receptacle, an outlet valve for closing the 75 drain outlet, an element connecting the valve and cover, an inlet conduit connected with the drinking receptacle, an inlet valve to control the passage of water through the inlet conduit into the drinking receptacle 80 and having an operative connection with the cover, and a strainer element arranged within the drinking receptacle near and in advance of the drain outlet, the overflow conduit, the outlet valve, and the connecting element of the outlet valve, to prevent foreign 85 material passing into the drain outlet and overflow conduit and also serving as a guard for the outlet valve and its connecting element, to prevent the animal's mouth from 90 contacting therewith.

2. In apparatus of the character described, 95 a drinking receptacle provided in its bottom with a drain outlet; an overflow conduit for the drinking receptacle arranged near the drain outlet; a cover hinged to the drinking receptacle; an outlet valve for closing the drain outlet; an element connecting the outlet valve and cover and extending within the receptacle; means operated by the movement 100 of the cover to supply water into the drinking receptacle; and an approximately vertically arranged apertured plate disposed within the drinking receptacle near and in advance of the drain outlet, overflow conduit, outlet valve, and connecting element of the outlet valve to prevent foreign material passing into the drain outlet and overflow conduit and also serving as a guard for the outlet valve and its connecting element, to prevent the animal's mouth from 105 contacting therewith.

3. In apparatus of the character described; 110 a drinking receptacle provided in its bottom and near one corner thereof with a drain outlet; an overflow conduit arranged within said corner of the drinking receptacle; a cover hinged to the drinking receptacle; an outlet valve for the drain outlet; an element connecting the outlet valve and cover; means 115 for supplying water to the receptacle; and an apertured approximately vertical plate disposed obliquely in said corner of the receptacle, near and in advance of the drain outlet, the overflow conduit, the outlet valve, 120 and the connecting element of the outlet valve, to prevent foreign material passing into the drain outlet and overflow conduit and also serving as a guard for the outlet valve and its connecting element, to prevent 125

130

the animal's mouth from contacting therewith.

4. In apparatus of the character described; a drinking receptacle provided in its bottom 5 with a drain passage which is inclined toward the rear end of the receptacle, said drain passage being provided with a drain outlet; an overflow conduit disposed within the drinking receptacle and arranged near 10 the drain outlet, said overflow conduit and drain outlet being disposed near the rear end of the receptacle in one corner thereof; a cover hinged to the drinking receptacle; an outlet valve for the drain outlet; an element
- connecting the outlet valve and cover; means 15 for supplying water to the receptacle; a substantially vertical apertured plate disposed obliquely in the said corner of the receptacle, near and in advance of the drain outlet and overflow conduit, and having a depending 20 extension passing into the drain passage; and a substantially horizontal plate secured to the upper end of the apertured plate and being tapered to fit within the corner of the receptacle.

In testimony whereof I affix my signature.

JOHN MINOR BOTT'S LEWIS.
